FOLDING BED AND CABINET UNIT

Karl Ossian Enewold Jönsson, Stockholm, Sweden

Application May 16, 1947, Serial No. 748,488
In Sweden April 2, 1946Section 1, Public Law 690, August 8, 1946
Patent expires April 2, 1966

3 Claims. (Cl. 5—155)

1

This invention relates to folding bed and cabinet unit combinations. More particularly, it is concerned with constructions comprising a cabinet and one or more bedsteads, adapted to pivot about points in their side members so that any bedstead, which is comprised of three pivotally interconnected bed frame members, may be folded together and turned to a position within the cabinet, or extended horizontally by unfolding to provide an operative bed structure perpendicular to the cabinet. The bed frame members can be constructed from angle irons spanned by a mattress support in the form of chain or spring design.

A principal object of the invention resides in the provision at the intermediate bed frame member of loosely suspended supporting bars, the free end portions of which are slotted or notched, and adapted, when the bed frame members are lowered and extended into their position of use, automatically to engage a transverse brace extending between two supporting legs carried by the outer end of the inner bed frame member, and thereby support the intermediate bed frame member.

It is a further object of this invention to provide a folding bed construction having the automatically operating supporting bars for the supporting legs in which the intermediate bed frame member is adapted to take a vertical position between the other two bed frame members when the latter are folded on one another, in order that the bed may be conveniently swung as a unit into the cabinet.

A folding bed and cabinet unit of the character indicated possesses a number of advantages. The bedsteads are readily manageable. They are also economical in use, because the bed clothes, the mattress, and the flexible bed bottom or mattress support are bent at only a slight curvature on the intermediate bed frame member, thus minimizing wear on the bed clothes. The compactness of the combination permits the use of a relatively low cabinet that can serve also as a shelf.

These and other advantages and particular features of improvement will be more apparent from the following specification taken in connection with the accompanying drawing illustrating a preferred embodiment of the invention.

In the drawing:

Fig. 1 is a partially sectioned side elevation showing a bed housing or cabinet having the front wall removed; with the bed frame members in their operative position for use;

Fig. 2 is a similar side elevation view showing the bed frame members folded together and ready to be swung upwardly into the cabinet;

Fig. 3 shows by a similar side elevational view the final position assumed by the folded bed frame members after they have been swung into the cabinet and the supporting legs have been withdrawn;

Fig. 4 is a somewhat enlarged side elevation of one of the supporting bars or struts;

Fig. 5 is an end elevational view showing the inner pair of supporting legs united by a transverse brace construction;

Fig. 6 is a partial plan view of one side of the bed frame members and of the mesh type of bottom or mattress support.

In the illustrative embodiment of this invention as shown in the drawing, a vertical rectangular cabinet C is arranged to support and to provide a housing for a folding bed B. A pair of oppositely disposed pivot pins 1 (of which only one is shown) are arranged to provide a horizontal pivot axis for an inner bed frame member 2, said pins 1 being disposed on the opposite sides of the frame member 2 in an intermediate position that is somewhat closer to the inner end.

As shown best in Figs. 1 and 2, a transverse brace 3, which is downwardly depressed as shown in Fig. 5, and an intermediate transverse brace 4 of rod shape interconnect a pivotally mounted pair of supporting legs 5 and 6 for the outer end portion of the inner bed frame member 2. The supporting legs 5 and 6 are preferably spring-actuated as indicated toward the inward or collapsed position shown best in Fig. 3. The legs 5 and 6 are formed with inwardly turned lower ends to provide effective floor abutting surfaces.

The free end of the outer bed frame member 7 may be swung to its position of use by means of a pair of spring-actuated supporting legs 8 interconnected by transverse bracing means similar to those described for legs 5 and 6.

The opposite sides of the inner and outer bed frame members 2 and 7 are provided with upstanding, longitudinally extending rails 9, 9 for laterally supporting the bed clothes.

As indicated in Fig. 1 and shown best in Fig. 6, the ends of the intermediate bed frame member 10 are pivotally connected by means of bolts or rivets to horizontal projections 11 extending from the sides of the adjacent ends of the inner and outer bed frame members 2 and 7. In this preferred embodiment the sides of the inner, outer and intermediate bed frame members 2, 1, and 10 are constructed of angle irons, the flanges of which are arranged to provide horizontal top and side surfaces, as shown in the drawing and for other purposes which will be explained.

55 A pair of supporting bars or struts 12, intercon-

3

nected by another transverse brace 3, are each pivotally connected adjacent a corner of one end to the respective outer portions of the sides of the intermediate bed frame member 10, and preferably by the same bolts or rivets that interconnect the bed frame members 7 and 10. In operative position these struts 12 act between their pivotal connections and the transverse brace 4 of legs 5 and 6 to support the intermediate frame member 10 and the outer frame member 7 at their adjacent, pivoted end portions.

Referring to Figs. 1 and 4, it will be observed that each strut or supporting bar 12 is eccentrically pivoted by a corner of one end to accommodate inward pivotal movement toward the undersurface of one side of the intermediate frame member 10, and to limit pivotal movement in the other direction by engagement of the other corner with the undersurface of the horizontal flange of said one side of the intermediate frame member. As shown in Fig. 4, a flat bar strut 12 is rounded at the corner adjacent its pivotal connection and extended at the other corner with an end edge of predetermined angularity to the longitudinal axis of the strut to stop the strut in the required acute angular relation to the intermediate frame member 10.

The longer two supporting legs 5 and 6 for the inner bed frame member 2 have their respective upper ends eccentrically pivoted and formed in the manner described for the supporting bars or struts 12, with the exception that the angular relation of the longitudinal axes is such as to stop the legs 5 and 6 in a forwardly inclined, acute angle relation to the intermediate bed frame member 10, as best shown in Fig. 1. The spring-actuated supporting legs 8 for the outer bed frame member 7 may also have their upper pivoted ends formed and arranged in substantially the same manner as the legs 5 and 6.

Fig. 4 also shows the particular formation of the free or lower end of the strut 12 to provide a slit or notched formation 13 for interengagement with the transverse rod-shaped brace 4 between legs 5 and 6.

After the bed B in folded condition has been pivoted to the horizontal position shown in Fig. 2 with the supporting legs 5 and 6 extended and engaging the floor surface, outward and downward pivoting of the intermediate bed frame member 10 will cause the freely pivoted supporting struts 12 to fall into the angular position shown in Fig. 1 in which they are automatically caused to engage the rod 4 with their notched portions 13, and thus secure and maintain the strut 12 in operative relation to the supporting legs 5 and 6 of the inner bed frame member 1. As will be obvious, release and collapsing or pivoting of the struts 12 and legs 5 and 6 toward their respective bed frame members 10 and 2 is accomplished by reverse pivoting and folding of the bed B.

The upper cross braces 3 between all of the supporting leg pairs and the supporting bars or struts are extended below the respective pivots thereof to permit the flexible bed bottom 14 to yield downwardly. In order to provide proper guidance for the supporting legs in a lateral direction, the ends of their transverse braces 3 are bent upwardly as shown to bear on the supporting legs to which they are welded.

When the several bed frame members are to be swung up and into the cabinet C from the horizontally extended position of use, the transverse brace 3 of the supporting legs 8 is first

4

grasped for the purpose of raising the corresponding bed frame member 7. When the outer bed frame member 7 has reached its vertical position, the transverse edge of the side of this bed frame member adjacent the projection 11 will bear on the upper side of the intermediate bed frame member 10, so that the latter will be caused to follow in movement to the completely folded bed position of Fig. 2. When the bed B is in the folded horizontal position of Fig. 2, the end of the inner bed frame member 2 may be raised and swung as a unit into the cabinet C to the storage position of Fig. 3. The outer bed frame member 7 is at this time hanging on the intermediate bed frame member 10 and standing on the floor of the cabinet, while said intermediate bed frame member is in turn suspended on the abutting end of the inner bed frame member 2. The end of the outer bed frame member 7 is thus caused to support and maintain the outer bed frame member 7 and the inner bed frame member 2 in vertical position.

It will now be understood that during the upward swinging movement of the bed frame members the spring-actuated supporting legs 5, 8 fall into the respective bed frame members, while the supporting bars or struts 12 fall of their own weight into a position parallelling the vertically extending intermediate bed frame member 10. When the bed B is folded up into the cabinet C, the bed clothes are retained by means of straps, bands or the like arranged between the rails 9, and the front opening of the cabinet may then be covered by a piece of drapery, doors or the like.

When two or more beds are to be arranged within a cabinet, vertical partitions will be provided, and such partitions will be fitted with pivot pins of the respective beds secured therein.

40 What I claim is:

1. A folding bed and cabinet unit comprising a cabinet structure having a front opening; a bed including pivotally interconnected inner, intermediate, and outer bed frame members, said inner frame member being pivotally mounted within the cabinet for rotation about a transverse horizontal axis; a supporting leg eccentrically pivoted by a corner of one end on each of opposite outer end portions of said inner frame member to accommodate inward pivotal movement toward the undersurface of said inner frame member and to limit pivotal movement in the opposite direction by engagement of the other corner of said end with the undersurface of said inner frame member; a transverse brace interconnecting said supporting legs intermediate their lengths; a strut eccentrically pivoted by a corner of one end on each of opposite outer end portions of said intermediate frame member to accommodate inward pivotal movement toward the undersurface of said intermediate frame member and to limit pivotal movement in the opposite direction by engagement of the other corner of said end with the undersurface of said intermediate frame member, the lower end of each of said struts having a notch formation to receive said transverse brace as said intermediate frame member is swung into a horizontal position and to secure said struts in operative relation to the supporting legs of said inner frame member; and supporting legs secured to the outer portions of said outer frame member.

2. A folding bed and cabinet unit comprising a cabinet having spaced vertical side members defining a front-opening, bed-receiving space; a

bed having inner, intermediate, and outer bed frame members each having spaced opposite sides, said intermediate frame member being pivotally connected by the opposite ends of its sides to the adjacent ends of the respective sides of said inner and outer frame members; pivot means connecting each side of said inner frame member to the adjacent vertical side member of the cabinet for rotation about a horizontal axis; a pair of supporting legs each pivotally connected adjacent a corner of one end to the respective outer end portion of each side of said inner frame member; a transverse brace interconnecting said supporting legs intermediate their lengths, the said one end of each of said supporting legs being rounded at the corner adjacent its pivotal connection to accommodate inward pivotal movement toward the undersurface of said inner frame member, and extending at the other corner to limit pivotal movement in the opposite direction by engagement of the extending corner with the undersurface of said inner frame member; a pair of struts each pivotally connected adjacent a corner of one end to the outer portion of one side of said intermediate frame member, the said one end of each said struts being rounded at the corner adjacent its pivotal connection to accommodate inward pivotal movement toward the undersurface of said intermediate frame member and extending at the other corner to limit pivotal movement in the opposite direction by engagement of the extending corner with the undersurface of the corresponding side of said intermediate frame member, the lower end of each of said struts being notched to receive said transverse brace and maintain said struts in operative relation to the supporting legs of said inner frame member; and an additional pair of supporting legs each pivotally connected by one end with an outer end portion of one side of said outer frame member.

3. A folding bed and cabinet unit comprising a cabinet having spaced vertical sides defining a front opening; a bed having inner, intermediate, and outer bed frame members each having spaced opposite sides, said intermediate frame member being pivotally connected by the opposite ends of its sides to the adjacent ends of the respective sides of said inner and outer frame members; pivot means connecting each side of

said inner frame member to the adjacent vertical side of the cabinet for rotation about a horizontal axis; a pair of supporting legs each pivotally connected by the corner of one end to the respective outer end portion of each side of said inner frame member; a transverse brace of rod shape interconnecting said supporting legs intermediate their lengths, the said one end of each of said supporting legs being rounded at the corner adjacent its pivotal connection to accommodate inward pivotal movement toward the undersurface of said inner frame member, and extended at the other corner to limit pivotal movement in the opposite direction by engagement of the extended corner with the undersurface of said inner frame member; a spaced pair of interconnected struts each pivotally connected adjacent a corner of one end to the outer portion of one side of said intermediate frame member, the said one end of each said struts being rounded at the corner adjacent its pivotal connection to accommodate inward pivotal movement toward the undersurface of said intermediate frame member and extending at the other corner to limit pivotal movement in the opposite direction by engagement of the extending corner with the undersurface of the corresponding side of said intermediate frame member, the lower end of each of said struts being notched to receive said transverse brace as said intermediate frame member is swung into a horizontal position and to secure said struts in operative relation to the supporting legs of said inner frame member; and an additional pair of interconnected supporting legs mounted on the outer end of the corresponding side of said outer frame member.
